UNITED STATES PATENT OFFICE.

GEORGE A. FUHS, OF MADISONVILLE, KENTUCKY.

WINDOW-SHADE BRACKET.

1,090,043.

Specification of Letters Patent. Patented Mar. 10, 1914.

Application filed June 3, 1913. Serial No. 771,451.

To all whom it may concern:

Be it known that I, GEORGE A. FUHS, a citizen of the United States, residing at Madisonville, in the county of Hopkins and State of Kentucky, have invented new and useful Improvements in Window-Shade Brackets, of which the following is a specification.

This invention relates to window shade and curtain supports and one of its objects is to provide supporting means which may be employed upon any ordinary type and width window frame, which will support shade rollers of different widths and at different heights upon the window frame, and which may be readily applied to and removed from the frame at will.

A further object of the invention is to provide a window shade and curtain hanger which may be used without marring the woodwork.

The invention consists of the features of construction, combination and arrangement of parts, hereinafter fully described and claimed, reference being had to the accompanying drawings, in which:—

Figure 1 is a view in elevation of a window frame showing the application of the invention. Figs. 2 and 3 and 4 are horizontal transverse sections on the line 2—2, 3—3 and 4—4 of Fig. 1. Fig. 5 is a fragmentary detail view of one of the guide plates and associated shade supporting member.

Referring to the drawing, 1 designates a window frame for casing of any ordinary construction, at the opposite sides of the head portion of which are arranged attaching brackets 2. These brackets extend across the front of the casing and have bearing arms 3 arranged to engage the sides of the casing. If desired, these arms may be provided with spurs to enter the woodwork, to assist in holding the attaching brackets in position. As shown the brackets are connected by a coiled spring 4, whereby they are drawn together and held in clamping engagement with the frame. The brackets 2 carry suitable supporting brackets 5 adapted to receive curtain poles 6 or the like, and to said brackets 2 are also secured the upper ends of depending guide plates 7 which bear against the surfaces of the jambs

of the window frame. These plates carry at their lower ends clamping members 8 having laterally bent ends or arms to engage the sides of the jambs, whereby the lower ends of the guide plates are held in proper position. The longitudinal side edges of each guide plate are bent inwardly 60 to provide beads 9 and 10, which provide between them a grooved guideway 11. Slidably in the guideways of the guide plates are guide members 12 suitably fixed to carrier brackets 13, which are thus made vertically adjustable upon the window frame to any desired elevation. Each of these carrier brackets 13 is provided with a grooved guideway, and slidably mounted in the grooved guideways of the carrier brackets are shade roller supporting brackets 14 and 15, which may be of any preferred construction. These brackets may be adjusted in the carrier brackets in a direction transversely of the frame, so that they may be spaced a greater 75 or less distance apart to suit any desired length of shade roller. A coiled spring 16 connects the two carrier members 13 and operates to draw the clamping members 8 against the sides of the jambs, such clamps 80 thus coacting with the clamping brackets 2 to hold the supporting elements upon the frame in such manner that they may be conveniently detached therefrom when occasion requires and transferred to another frame. 85 It will be observed that this construction not only adapts the supporting members to be mounted upon different frames, and frames which vary in width, but also for supporting a shade roller of any length at 90 any desired elevation, the advantages of which will be apparent. Inasmuch as the supporting elements are not nailed, screwed or otherwise fastened to the frame, they may be conveniently detached and when in 95 use will not mar or otherwise injure the woodwork. The beads 9 of the guide plates are preferably provided with scale graduations of a similar character, so that the carrier brackets 13 may be accurately adjusted 100 to like elevations on the guide plates.

I claim:—

A support of the character described comprising upper and lower pairs of clamping members, guide plates carried by the clamping members and provided with guide ways,

carrier brackets having guide members vertically slidable in said guide ways, said carrier brackets also having guide ways, supporting brackets slidably mounted in the 5 guide ways of the carrier brackets for relative adjustment, an elastic connection between the upper pair of clamping members, and an elastic connection between the carrier brackets, said elastic connections serv-

ing to draw the clamping members into engagement with the sides of a window frame.

In testimony whereof I affix my signature in presence of two witnesses.

GEORGE A. FUHS.
